UNITED STATES PATENT OFFICE.

WILLIAM D. BOYCE, OF NEW YORK, N. Y.

SMOKE-CONSUMING DEVICE FOR FIRE-BOXES.

1,276,166.

Specification of Letters Patent. Patented Aug. 20, 1918.

Application filed January 22, 1917. Serial No. 143,756.

To all whom it may concern:

Be it known that I, WILLIAM D. BOYCE, a citizen of the United States, residing at New York, in the county of New York and 5 State of New York, have invented certain new and useful Improvements in Smoke-Consuming Devices for Fire-Boxes, of which the following is a full, clear, and exact description, reference being had to the accompanying drawings, forming a part hereof.

My invention has relation to improvements in smoke-consuming devices for fire-boxes; and it consists in the novel features of construction more fully set forth in the 15 specification and pointed out in the claims.

The present invention is an improvement on the structure of the smoke-consuming device forming the subject-matter of U. S. Letters Patent numbered 1,071,689, issued 20 to me under date of September 2, 1913, and has for its object the elimination of certain objections inherent in the structure of the patented device, notable among which is the tendency of the air plate or casting which 25 supplies the air to the fire-box to burn out or disintegrate as a result of the corroding action of the fire gases and incandescent fuel to which it is at all times exposed. Another objection to the patented structure is, that in 30 cases where the depth of fuel in the fire box happens to reach to the top of the slots through which the air is admitted, the air currents must force their way through the fuel before mingling with the steam above 35 the fuel, the efficiency of the final mixture to consume the smoke being in a large measure impaired. This gives rise to the further objection that the service of the air slots in the patented structure is not uniform, the 40 slots being at times covered by fuel and at other times exposed. The present improvement offers the following advantages, to wit: (1) Excess of air is avoided, only a sufficient amount being admitted to serve as a proper 45 complement to the oxygen furnished by the steam component. (2) There is no danger of burning out the supply pipe leading to the steam nozzle. (3) The steam nozzle is susceptible of any desired adjustment. (4) 50 The air is not required to work its way through the fuel charge, being always admitted to points above the surface of the charge. (5) The air service is uniform because the passage of the air into the fire box 55 is free and unobstructed at all times. (6) It is simple. (7) It presents a better loca-

tion for the points of entry of the air into the fire-box. (8) The air is always above the surface of the fuel charge irrespective of the depth of the charge. (9) The parts 60 are readily replaced when worn or deteriorated. (10) The steam jets have great penetrating power, thoroughly intermingling with the admitted air. The improvement possesses further and other advantages 65 better apparent from the following detailed description thereof in connection with the accompanying drawings in which—

Figure 1 represents a plan of the invention, parts of the fire-box and boiler being 70 shown in dotted lines; Fig. 2 is a side elevation of the parts shown at the rear of the boiler in Fig. 1, with the air hood partly broken away; Fig. 3 is a front elevation of the steam risers and their appurtenances, 75 and of the hoods in the rear thereof, the rear water-leg of the boiler being shown in dotted outline; Fig. 4 is an enlarged middle vertical longitudinal section through the spray-head and jet elbow, and of the hollow 80 stay bolt receiving the long leg of the jet elbow, the inner and outer sheets of the rear water leg being likewise in section; Fig. 5 is a top plan of the spray-head with parts broken away; and Fig. 6 is a front elevation 85 of the spray-head.

Referring to the drawings, 1, 1', and 2, 2, represent piping leading from the engine exhaust and 2', 2', live steam pipes leading from the boiler, for supplying exhaust or 90 live steam to the risers 3 which carry the steam to the spray-heads or nozzles 4 located in the fire-box F. In the present improvement the risers 3 are disposed on the outside of the rear water-leg L of the boiler B (a 95 locomotive boiler being herein shown by way of example), there being a riser on each side of the charging door D leading to the fire box. The connection between the riser 3 and spray head 4 is made through 100 the water-leg, the latter being provided at points between the charging door and each side of the water-leg and above the surface of the fuel charge in the fire-box, with clusters of specially provided hollow stay bolts 5 105 through which air is admitted into the fire-box, one of said hollow stay bolts 5' being availed of to receive and support the connecting members between the riser and spray head. To the upper terminal of the riser is 110 screwed an elbow 6 to which is in turn screwed a nipple 7, said nipple being con-

5 nected by a coupling 8 to a jet elbow 9 projecting into the fire-box, the short leg of the elbow being provided with a close nipple 10 to which in turn the spray head 4 is screwed, 10 suitable set screws 11, 11', being provided to hold the parts against movement when once they are properly adjusted. The spray-head 4 is provided with the usual slit *s* for projecting jets of steam across the fire box to 15 mingle with the complement of air admitted thereinto through the hollow stay bolts 5. As shown in the drawings, the stay bolt 5' of the series incloses the connecting members 7, 8, and the long leg of the member 9, thereby protecting these parts against 20 direct contact with the water in the water-leg. The coupling 8 and nipple 10 permit the members 9 and 4 to be adjusted to any position angularly, the member 9 being rotatable about the axis of the long leg thereof, and the member 4 being rotatable about its 25 own axis and that of the nipple 10 alined therewith. The character of adjustment is shown by the dotted position of the parts in Fig. 4 where the short leg of the jet elbow 9 is turned downward as against the upturned position shown by the full lines in said figure. The hollow stay bolts 5 are protected by a hood 12 secured to the rear wall 30 of the water-leg L in any approved mechanical manner, the hood being open at the bottom and extending to the bottom of the water leg. The air passes up through the chamber C formed by the hood with the 35 water-leg whence it enters the hollow stay bolts passing thence directly into the fire box above the surface *x* of the fuel charge. The hood likewise diverts any back-flash through the hollow stay-bolts to the bottom 40 of the hood thereby protecting the clothing of the fireman from the flame, and preventing possible injury to the fireman.

45 The direction of projection of the steam jets from the spray heads 4 is toward the center of the fire-box substantially along lines indicated by *t*, *t*, in Fig. 1, although the angle of projection relatively to the center longitudinal line of the fire box may be varied according to requirements, since the spray 50 head is rotatable about its axis, making it possible to adjust the slits *s* angularly to any degree. The elevation of the steam jets relatively to the surface of the fuel charge may also be adjusted, since the spray 55 head can be swung in a vertical plane about the axis of the long leg of the jet elbow 9. The spray head is thus adjustable both vertically, and rotatably about its axis, making it possible to accurately adjust the paths of 60 projection of the steam jets to suit conditions. In the present improvement no portion of the device is exposed to the fuel and fire gases except the inner leg of the member 9 and the spray-head 4, and the latter can readily be renewed when worn or dis-

integrated. There is thus little to repair once the device is installed on the boiler, and in this respect the installation is a decided improvement over structures in which the air plate and steam riser are within the fire box and constantly exposed to the destructive effects of the fire. The number and position of the clusters of hollow stay-bolts 5 are such that they serve to conduct to the right place the proper complement of air intended to be mingled with the steam projected into the fire box from the spray heads 4, so that at all times, and by a proper control of the steam admitted on the part of the engineer, the mixture can be made exact to fulfill its function as a perfect and highly efficient smoke consumer. In cases where a locomotive is standing still or not running (so there is no exhaust) the engineer in order to burn up the smoke admits live steam 85 into the pipes by manipulating the blower valve V as understood in the art.

To increase to the maximum the penetrating power of the jet issuing from the slit *s* of the spray-head, I widen the slit preferably at the center so as to form the enlarged opening *o* through which the steam issues without material disssipation or spreading, causing the jet to carry further in the direction of original projection and more effectively penetrate the air and gases in the fire box. The result is a more thorough intermingling of steam and air and a more complete combustion of the smoke and unconsumed products. In practice I may have a plurality of enlargements or openings such as *o* and I do not wish to be limited to the single enlargement shown in the drawings.

I do not of course wish to be limited to the use of hollow stay-bolts as here arranged for admitting the air complement into the fire-box, or to stay-bolts arranged in clusters as here shown, any equivalent method or methods being contemplated under my invention provided of course that the air so admitted shall discharge through the rear water-leg ("rear" when speaking of locomotive boilers of course) above the surface of the fuel charge on either side of the charging door, and in proper quantities to constitute the necessary complement to the steam component projected into the fire-box by the spray-heads 4 or any equivalent thereof. Neither do I wish to limit the invention to the use of spray-heads such as 4, any equivalent jet nozzle being contemplated by my invention. Furthermore, I do not wish to be understood as restricting the application of the invention to locomotive boilers, or to any special kind of fuel burnt in the fire box. It may be solid, liquid or gaseous; if solid, it may be in large or small pieces, or powdered. Wherever necessary the system is provided with controlling valves, the blower valve V above referred to being on the order 130

of that shown in my patent aforesaid and constituting a part of the present equipment. Features shown in the drawings but not alluded to are well understood by those skilled in the art, and a description thereof in the present connection is unnecessary.

Having described my invention what I claim is:

1. In a locomotive boiler provided with a fire-box bounded in the rear by a water-leg having a fuel charging door, one or more hollow stay-bolts disposed in the water-leg on either side of the charging door for admitting atmospheric air to the fire-box above the surface of the fuel charge, means for causing the inflowing air to traverse the outer wall of the rear water-leg before entering said stay-bolts, and means for conducting steam into the fire-box through the rear water-leg independently of the air delivered through the hollow stay-bolts aforesaid.
2. In combination with a locomotive fire-box having a rear water-leg provided with a charging door, a cluster of hollow stay-bolts disposed through the water-leg on either side of the charging door for delivering air to the fire-box to points above the fuel charge, a hood for covering said stay-bolts and conducting the air thereto from points near the bottom of the outer wall of said water-leg, an additional hollow stay-bolt disposed through the water-leg, and a pipe discharging through said stay-bolt and projecting into the fire-box a complement of steam independent of the streams of air delivered through the remaining stay-bolts.
3. In a locomotive boiler provided with a fire-box bounded in the rear by a water-leg having a fuel charging door, one or more hollow stay-bolts disposed in the water-leg on either side of the charging door for admitting atmospheric air to the fire-box above the surface of the fuel charge, means for causing the inflowing air to traverse the outer wall of the rear water-leg before entering said stay-bolts, and means in the region of the rear corner of the fire-box for project-

ing toward the center of the fire-box a complement of steam to mingle with the air entering through the hollow stay-bolts.

4. In a locomotive boiler provided with a fire-box bounded in the rear by a water-leg having a fuel charging door, a spray nozzle near the rear corner of the fire-box discharging steam toward the center of the fire-box, one or more hollow stay-bolts disposed in the rear water-leg on either side of the charging door for admitting atmospheric air to the fire-box above the surface of the fuel charge, and a hood adjacent the outer wall of the rear water-leg for covering said hollow stay bolts and conducting air thereto from points contiguous to said wall.

5. In a locomotive boiler provided with a fire box bounded in the rear by a water-leg having a fuel charging door, one or more hollow stay-bolts disposed in the water-leg for admitting atmospheric air to the fuel charged through said door, and a hood for protecting the outer ends of the stay-bolts comprising a sheet provided with marginal flanges forming with the rear wall of the water-leg an open bottomed air chamber operating to direct the air currents to the stay-bolts, the hood terminating near the bottom of the water leg whereby any back flash is diverted downwardly.

6. In a locomotive boiler provided with a fire box bounded by a water-leg, one or more hollow stay-bolts disposed in the water-leg for admitting atmospheric air to the fuel in the fire box, and a hood for protecting the outer ends of the stay-bolts comprising an open bottomed box-like member positioned adjacent the water leg and extending to a point near the bottom thereof for conducting atmospheric air to the hollow stay-bolts and for diverting the back-flash toward the bottom of the water-leg.

In testimony whereof I affix my signature in presence of two witnesses.

WILLIAM D. BOYCE.
